UNITED STATES PATENT OFFICE

JAMES B. GILLIAM, OF KANSAS CITY, MISSOURI

WASTE-PICKING MACHINE

Application filed June 20, 1928. Serial No. 286,875.

This invention relates to combing or carding, and its general object is to provide a waste picking machine primarily designed for reclaiming packing or waste removed from journal boxes of railroad cars, locomotives and the like, and one that will separate the short or worn out fiber, grit, gravel, metal particles and other foreign matter from the long fiber which can be reoiled and again used for packing the boxes.

A further object of the invention is to provide a machine of the character set forth, that performs its function in an expeditious manner, is simple in construction, inexpensive to manufacture and efficient in operation and service.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a top plan view of the machine forming the subject matter of the present invention.

Figure 2 is a longitudinal sectional view taken through the machine and receptacles.

Figure 3 is an end elevation of the machine.

Figure 4 is a top plan view of the toothed roller.

Figure 5 is a similar view of the toothed plate.

Referring to the drawings in detail, it will be noted that the machine is shown as being constructed from sheet metal throughout and includes a body 1 having secured thereto and depending from the four corners thereof legs 2. The body is substantially elongated and includes side and end walls indicated respectively by the reference numerals 3 and 4. The bottom of the body is made up of a pair of outlet chutes arranged in spaced parallelism with respect to each other, as best shown in Figure 2, and these chutes each in-

clude converging downwardly inclined walls 5 arranged in circular formation and have formed with their lower edges flanges 6.

One of the end walls is disposed below the top of the body and secured to the side walls and transversing the body is a feed table 7 which is disposed at an inclination and has formed with its outer edge a horizontal flange 8 overlying the upper edge of the last mentioned side wall and extending outwardly beyond the body as best shown in Figure 2.

Passing through the side walls of the body approximately midway their ends is a shaft 9 which has its ends disposed in bearings 10 secured to the outer sides of the side walls through the instrumentality of brackets 11. This shaft has fixed thereto a cylinder 11' which has secured to its outer surface and arranged in equi-distantly spaced relation with respect to each other, a plurality of teeth 12 arranged in parallel rows.

These teeth are all inclined in one direction and cooperate with teeth 13 secured to and extending from a concave plate 14 which is shaped to follow the curvature of the cylinder and is secured to the side walls 3. The teeth 13 are also inclined, but are disposed at an inclination opposite to that of the teeth 12.

Bridging the top of the side walls 3 slightly beyond the central portion of the body is a cross strip 15 which has hingedly secured thereto as at 15' a curved cover 16 for the cylinder. The cover 16 is provided with stop strips 17 arranged on the inner surface of each of the side walls and which supports the cover in its closed position as shown. A flat cover 18 is provided for the body and is hingedly secured as at 18' to the end wall 4 that is disposed opposite the short wall as shown. This cover 18 extends from its side wall to the cross strip 15, and each of the covers is provided with a handle 19 whereby they may be swung on their hinges as will be apparent.

Secured to one side wall of the body are right angle brackets 20 which are adapted to support a motor having suitable connection with the shaft 9 for driving the cylinder.

Disposed below the outlet chutes are re-

ceptacles 21, one of which is adapted to receive the worn or short fibers and foreign matter, while the other receives the long fiber which may be reused.

5 From the above description and disclosure of the drawings, it will be obvious that I have provided a waste picking machine that separates the short or worn fiber and foreign matter from the long fiber and in the operation of the machine, the packing or waste is fed to the teeth of the revolving cylinder and the plate 14, and due to the novel arrangement of the teeth of these members, they operate in conjunction with each other to 10 set up a combing or carding action, as the teeth 13 during the operation of the cylinder at a certain required speed, strike the material fed into the machine with great force, and with this force together with the arrangement of the teeth, separation of the fiber from each other and the foreign matter therefrom will be complete. In other words, the action of the teeth will remove the short or worn fiber and foreign matter from the long 15 fibers, and the short fibers and foreign matter will drop through the slots 22 formed in the plate 14 into the receptacle below the chute that is arranged adjacent the plate 14, while the long fiber will be carried by the teeth 12 20 to the other chute for disposal in the other receptacle.

The speed of the cylinder creates a considerable volume of air which is forced through the material, while the latter is passed over 25 the plate 14 and this air blows small particles of dirt and dust from said material as will be apparent. The teeth of the cylinder have a striking effect on the material which may be entangled or knotted, and this 30 striking action tears the material apart and forces the short fiber and foreign matter through the openings in the plate 14, while the long fiber is carried or delivered across the plate 14 to be deposited in the receptacle 40 below the cover 18.

45 Any of the long fiber that may cling to the teeth of the cylinder will fall therefrom due to the inclination assumed by these teeth when the latter are disposed above the last mentioned receptacle.

It is thought from the foregoing description that the advantages and novel features of my invention will be readily apparent.

I desire it to be understood that I may 55 make changes in the construction and in the combination and arrangement of the several parts, provided that such changes fall within the scope of the appended claims.

What I claim is:

60 1. A waste picking machine constructed of sheet metal and comprising a body, a cylinder mounted for rotation in said body, brackets secured to said body to support a motor for rotating said cylinder, teeth formed 65 with said cylinder and being arranged in

spaced rows, a longitudinally slotted concaved plate disposed in said body adjacent said cylinder, inclined teeth secured to said plate and cooperating with the teeth first mentioned, a feed table arranged at an inclination toward said cylinder and concaved plate, a chute disposed below said concaved plate, a chute arranged in parallelism with the chute first mentioned and disposed below a portion of said cylinder and receptacles for 70 the chutes. 75

2. A waste picking machine comprising a body, a toothed cylinder arranged in said body and having its teeth disposed at an inclination with respect thereto, a shaft passing through said body and securely receiving said cylinder for rotating the latter, bearings secured to the outer sides of said body and receiving the ends of said shaft, a toothed plate formed with slots and having its teeth 80 arranged at an inclination opposite from that of the teeth first mentioned and operating in conjunction therewith, a cross strip secured to the top of said body adjacent the toothed cylinder, a curved cover hingedly secured to 85 said cross strip and overlying the cylinder, a feed table inclined toward the cylinder, a pair of chutes disposed below the toothed plate and cylinder respectively and a cover 90 arranged above one of said chutes. 95

3. A waste picking machine comprising a casing including side and end walls, a toothed cylinder mounted for rotation between the side walls, and longitudinally spaced outlet chutes in the bottom of the casing below and upon opposite sides of the vertical center of the cylinder, a curved plate spaced from and arranged concentric with the cylinder above one of the outlet chutes and having openings therein, teeth extending from said plate 100 through the toothed cylinder and cooperating therewith, an inclined feed table disposed between and connecting the side walls of the casing and having its inner end disposed at the upper end of the curved plate, and a cover 105 for the top of the casing, said cover including a hingedly mounted curved section arranged concentric with respect to the cylinder and having its free end spaced above the inclined feed table to provide a restricted mouth. 110 115

In testimony whereof I affix my signature.

JAMES B. GILLIAM.
